SHEET METAL TUNING FORK

Donald R. Dailey, Leesburg, Va., assignor to Melpar, Inc., Falls Church, Va., a corporation of Delaware

Filed Mar. 26, 1965, Ser. No. 442,955

9 Claims. (Cl. 84—457)

The present invention relates generally to sheet metal tuning forks and more particularly to a fork having its tines mounted so they vibrate in the plane of the sheet.

Prior sheet metal tuning forks have been constructed by bending a strip of sheet metal into the shape of a U. The fork tines have been arranged so the thickness of the sheet vibrates in planes at right angles to the direction of forces that cause oscillation. Thus, the width of the sheet is subjected to the driving forces derived from a source of oscillatory energy. A typical example of such a prior art tuning fork is shown in U.S. Patent 3,106,124, issued to William P. Asten.

Stability of the oscillations deriving from a sheet metal tuning fork assembly is related to the mass ratio of the fork to the base assembly, such that a relatively high ratio can result in oscillations at a frequency different from the designed natural fork frequency. To achieve stability, it is incumbent upon tuning fork designers to provide a support having a mass at least equal to, and preferably considerably greater than, the mass of the fork. The most preferred manner for achieving this result for a modern, miniature device is to reduce the fork mass as much as possible so that the weight and size of the assembly is minimized. Since, however, fork mass and dimensions are a function of frequency, a rigidly prescribed parameter, an anomaly is seemingly reached between the parameters governing minimum fork assembly size and frequency.

I have found that this problem can be overcome, to a large extent, by stamping the fork as a sheet having a U shape and mounting the resulting structure so that the tines vibrate in the plane of the sheet. The natural frequency of the fork of the present invention is determined, primarily, by the tine length and width, with the thickness dimension having only a relatively small effect resulting from changes due to its spring tension properties. Actually, the sheet thickness need only be great enough to provide sufficient rigidity to the tines whereby fork vibrations and/or bending in planes other than those in which the sheet lie are precluded.

Because the width of the stamped tines in their direction of vibration can be made substantial according to the present invention, the fork mass necessary to achieve a particular frequency is reduced in comparison to the prior art devices. Because of the reduced fork mass, it is possible to provide a base of lower mass and still achieve stability. In consequence, the weight and size of the entire unit is reduced over what the prior art achieves for a unit having the same output characteristics.

By stamping the tines from sheet metal, the cost of fabrication is reduced considerably from the prior art, bent sheet metal fork. The stamping of multiple forks can be accomplished in a facile and simultaneous manner in comparison to the somewhat tedious and individual bending operations of the prior art.

It is, accordingly, an object of the present invention to provide a new and improved sheet metal tuning fork.

It is another object of the present invention to provide a sheet metal tuning fork in which the tines are stamped in a U-shape.

A further object of the present invention is to provide a sheet metal tuning fork wherein the tines vibrate in the plane of the sheet.

Still another object of the invention is to provide a sheet metal tuning fork wherein the width of the tines

2

in the plane of their vibration is appreciably greater than the thickness of the sheet metal.

An additional object of the invention is to provide a sheet metal tuning fork wherein sheet thickness has no substantial effect on frequency but is relied upon solely for maintaining fork rigidity.

Yet a further object of the invention is to provide a new and improved sheet metal tuning fork that is less expensive, has a smaller mass and occupies less space than prior art devices.

A still further object of the invention is to provide a new and improved tuning fork assembly having low mass tines mounted on a relatively small, low mass support, wherein the fork to support mass ratio is sufficiently low to enable stable oscillations to be derived.

The above and still further objects, features and advantages of the present invention will become apparent upon consideration of the following detailed description of one specific embodiment thereof, especially when taken in conjunction with the accompanying drawings, wherein:

FIGURE 1 is a perspective view of the sheet metal fork and support according to one embodiment of the invention;

FIGURE 2 is a side sectional view of the entire assembly, taken through the lines 2—2 of FIGURE 3.

FIGURE 3 is a front sectional view taken through the lines 3—3 of FIGURE 2;

FIGURE 4 is a top sectional view taken through the lines 4—4 of FIGURE 3; and

FIGURE 5 is a top view illustrating the positions of the tines at two different times during a period of oscillation.

Reference is now made specifically to the figures wherein U-shaped sheet metal fork 11, stamped from a highly permeable magnetic material, such as NI-SPAN-C, is mounted toward one edge of a rectangular support 12 that has sufficient thickness to provide adequate support for the fork. Fork 11 is bonded to support 12 by solder or welded joint 13 at the center of its leg 14 that joins tines 15 and 16 together. Support 12 is fixedly mounted on plate 17 by two screws 18 that thread into bores 19. The complete fork-support assembly is designed so that fork mass is considerably less than the support mass to achieve stable oscillations.

Cylindrical, drive and pick up coils 21 and 22, respectively, having permanent magnets 23 and 24 coincident with their axes, are fixedly positioned so their aligned longitudinal axes extend in a plane at right angles to the plane in which fork 11 lies and is substantially coincident with the plane containing the fork center line. Windings 21 and 22 extend almost to the face of fork 11, but no farther since their outer circumferences extend beyond the inner edges of tines 15 and 16.

Magnets 23, 24, coils 21, 22, as well as the electronic circuits necessary to provide a completely transistorized oscillator, are encapsulated or potted into a unitary, solid body 30 with a high temperature, stable plastic. In the encapsulating operation, mounting plate 17 for base 12 and header 20, both of which are metallic, are bonded to either end of body 30. The power and signal leads 31 for the transistor oscillator extend through insulated segment 32 in header 20.

By utilizing the tuning fork of the present invention, it is possible to mount the entire tuning fork oscillator in a sleeve-like metal (magnetic or non-magnetic) case 25 having approximate exterior dimensions of 1.5" length, $\frac{3}{4}$ " width and $\frac{5}{16}$ " breadth. Of this space, the tuning fork tines and base, driving and pickup coil magnet structures occupy an approximate volume of $1\frac{1}{8}$ " long, $\frac{3}{4}$ " wide and $\frac{1}{4}$ " in breadth. The total assembly, with leads attached, weighs less than one ounce.

The entire tuning fork assembly encapsulated in body 30 when slid into container 25 is such that fork 11 and

the exposed ends of magnets 23 and 24 are proximate to container wall 33. The unit possesses an optimum fork to support mass ratio, as a result of tines 15 and 16 being arranged so that the sheet metal thickness, denoted by reference numeral C, extends in the same direction as the axes of coils 21, 22. In addition, the construction employed wherein fork 11 is disposed along one wall of container 25, enables coils 21, 22 and magnets 23, 24 to be of maximum size, so that an output voltage of large amplitude is derived.

To provide maximum magnetic field coupling between windings 21, 22 and vibrating tines 15, 16, permanent bar magnets 23 and 24 are aligned with the winding axes and extend between the tines, almost to the wall of metal container 25. Magnets 23 and 24 are polarized so that the north pole of the former and the south pole of the latter are proximate fork 11. Hence, the D.C. magnetic reluctance path can be assumed as originating at the surface of magnet 24, closest to the free ends of tines 15, 16. The path continues, in parallel, through tines 15, 16 to the location of magnet 23 where it combines at the south pole thereof, and goes through that magnet to its north pole. The permanent magnetic field proceeds through permeable container 25 to a position opposite the south pole of magnet 24. From there, it jumps the air gap to the south pole of magnet 24 and proceeds through that magnet to its north pole.

The magnetic field flux variations deriving from coil 21 result in vibration of tines 15 and 16 with opposed velocities in the plane of the sheet. The rest position of tines 15 and 16 is shown in the top view of FIGURE 5 by the solid line rectangles denoted by reference numeral 26 while the most extreme inward position of the tines during a cycle of oscillation is illustrated by the dashed line rectangles denoted by reference numeral 27. It is noted that front edges 35 of the tines are always in the same plane during the entire oscillating cycle.

The natural resonant frequency of fork 11 is determined, to a large extent, by the width, B, and length, A, of tines 15 and 16. The fork frequency is not particularly affected by the tine thickness, C, which need only be great enough to provide sufficient rigidity to maintain the fork as a high Q, single frequency mechanical resonator. Hence, the starting material for fork 11 can be a typical piece of sheet metal that has a thickness in the range between 0.020 inch and 0.050 inch. The lower limit for the thickness of the sheets is the minimum thickness that provides the required rigidity, while the upper limit is set by the maximum fork to support ratio necessary to provide stable oscillations at the designed frequency.

In a typical embodiment actually constructed, the width, B, of stamped tines 15 and 16 was on the order of 0.100", their length, A, was approximately 0.75", sheet thickness was 0.025" and the distance between the outer tines 15 and 16 was approximately 3/8". The output frequency provided by this unit was on the order of 1400 c.p.s. with a Q of approximately 5000.

While I have described and illustrated one specific embodiment of my invention, it will be clear that variation of the details of construction which are specifically illustrated and described may be resorted to without departing from the true spirit and scope of the invention as defined in the appended claims.

I claim:

1. An electro-mechanical resonator assembly comprising a magnetically permeable, U-shaped, sheet metal tuning fork having a pair of tines joined by a leg between them, the thickness of said U being substantially equal to the thickness of said sheet, a support for said fork fixedly mounted to said leg so said tines vibrate in the plane of the sheet relative to the mounting position and electromagnet means being positioned to drive said tines so they vibrate in the plane of the sheet.

5 2. An electro-mechanical resonator assembly comprising a magnetically permeable, U-shaped sheet metal tuning fork having a pair of tines joined by a leg between them, the thickness of said U being sufficient to provide 10 rigidity to the fork and such that it has no substantial effect on the natural resonant fork frequency, said frequency being determined by the length and width of said tines, a support for said fork fixedly mounted to said leg so said tines vibrate in the plane of the sheet relative to the mounting position, and electromagnet means being positioned to drive said tines so they vibrate in the plane of the sheet.

15 3. The assembly of claim 2 wherein said thickness is at least 0.020".

4. The assembly of claim 2 wherein said thickness is in the range between 0.020" and 0.050".

20 5. An electro-mechanical resonator assembly comprising a magnetically permeable, stamped, U-shaped, sheet metal tuning fork having a pair of tines joined by a leg between them, the thickness of said U being substantially equal to the thickness of said sheet, a support for said fork fixedly mounted to said leg so said tines vibrate in the plane of the sheet relative to the mounting position and electromagnet means positioned to drive said tines so 25 they vibrate in the plane of the sheet.

30 6. An electro-mechanical resonator assembly comprising a magnetically permeable, stamped, U-shaped, sheet metal tuning fork having a pair of tines joined by a leg between them, the thickness of said U being sufficient to provide 35 rigidity to the fork and such that it has no substantial effect on the natural resonant fork frequency, said frequency being determined by the length and width of said tines, a support for said fork fixedly mounted to said leg so said tines vibrate in the plane of the sheet relative to the mounting position, and electromagnet means positioned to drive said tines so they vibrate in the plane of the sheet.

40 7. An electro-mechanical resonator assembly comprising a magnetically permeable, stamped, U-shaped sheet metal tuning fork having a pair of tines joined by a leg between them, the thickness of said U being sufficient to provide 45 rigidity to the fork and such that it has no substantial effect on the natural resonant fork frequency, said frequency being determined by the length and width of said tines, a support for said fork fixedly mounted to said leg so said tines vibrate in the plane of the sheet relative to the mounting position, said fork being mounted at one edge of said support, a mounting plate secured to said support at the edge opposite to said one edge, drive and pick up coils for said fork positioned to have 50 their longitudinal axes extending substantially along the plane containing the center line between the tines.

55 8. The assembly of claim 7 wherein the outer circumferences of said coils extend beyond the inner edges of said tines, and said coils extend proximate but not to the face of the fork, a permanent bar magnet lying along the longitudinal axis of each coil extending into said coil and between said tines.

60 9. The assembly of claim 8 further including a container having a pair of parallel walls, said fork and the ends of said magnet extending between said tines being disposed in proximity to one wall of said container.
